(57) **CLAIM**

The ornamental design for a chair, as shown and described.

DESCRIPTION

FIG. 1 is a front perspective view of a first embodiment of a chair;

FIG. 2 is a rear perspective view thereof;

FIG. 3 is a front elevational view thereof;

FIG. 4 is a rear elevational view thereof;

FIG. 5 is a right-side elevational view thereof, the left-side being a mirror-image;

FIG. 6 is a top plan view thereof; and

FIG. 7 is a bottom plan view thereof;

FIG. 8 is a front perspective view of a second embodiment of a chair;

FIG. 9 is a rear perspective view thereof;

FIG. 10 is a front elevational view thereof;

FIG. 11 is a rear elevational view thereof;

FIG. 12 is a right-side elevational view thereof, the left-side being a mirror-image;

FIG. 13 is a top plan view thereof; and

FIG. 14 is a bottom plan view thereof;

FIG. 15 is a front perspective view of a third embodiment of a chair;

FIG. 16 is a rear perspective view thereof;

FIG. 17 is a front elevational view thereof;

FIG. 18 is a rear elevational view thereof;

FIG. 19 is a right-side elevational view thereof, the left-side being a mirror-image;

FIG. 20 is a top plan view thereof; and

FIG. 21 is a bottom plan view thereof;

FIG. 22 is a front perspective view of a fourth embodiment of a chair;

FIG. 23 is a rear perspective view thereof;

FIG. 24 is a front elevational view thereof;

FIG. 25 is a rear elevational view thereof;

FIG. 26 is a right-side elevational view thereof, the left-side being a mirror-image;

FIG. 27 is a top plan view thereof; and

FIG. 28 is a bottom plan view thereof.

The parts delineated in broken lines are not part of the claimed design.

1 Claim, 28 Drawing Sheets
